CLAIM

The ornamental design for a glasses for 3-dimensional scenography, as shown.

DESCRIPTION

FIG. 1 is a front perspective view of a glasses for 3-dimensional scenography, showing our new design;

FIG. 2 is a front elevational view thereof;

FIG. 3 is a rear elevational view thereof;

FIG. 4 is a top plan view thereof;

FIG. 5 is a bottom plan view thereof.

FIG. 6 is a right side elevational view thereof; and,

FIG. 7 is a left side elevational view thereof.
